C. C. SHIPP,
METHOD OF MAKING THE CONNECTIONS FOR VENTILATING BOX BASES.

UNITED STATES PATENT OFFICE.

CLARENCE C. SHIPP, OF INDIANAPOLIS, INDIANA.

METHOD OF MAKING THE CONNECTIONS FOR VENTILATING BOX BASES.

Application filed October 3, 1921. Serial No. 505,119.

To all whom it may concern:

Be it known that I, CLARENCE C. SHIPP, a citizen of the United States, residing at Indianapolis, in the county of Marion and State of Indiana, have invented new and useful Improvements in Methods of Making the Connections for Ventilating Box Bases, of which the following is a specification.

This invention relates to the construction 10 of connections between the bases of ventilating boxes of steam-radiators and the sleeve extensions from the boxes in the walls of the houses through which outside-air is drawn into the houses, and the object is to construct a stronger and more durable connection 15 out of scrap metal than has heretofore been made out of whole sheet material, thereby making a better and a cheaper article.

In the accompanying drawing which is 20 illustrative of my invention, Fig. 1, is a plan view of a blank from which the upper side and flange of the device is formed. Fig. 2, is a like view of a blank from which the end flanges are made. Fig. 3, is the blank from 25 which the ends of the device are made. Fig. 4, is a front elevation of the completed connection. Fig. 5, is a top plan view of same. Fig. 6, is a front perspective view of the completed connection, and Fig. 7, is a vertical cross section of the box connection and 30 associated parts showing the manner of the assembly. Fig. 8, is a cross section, enlarged, of the folded joint.

As shown in Fig. 4, the top longitudinal 35 flange of my connection device is wider than the corresponding bottom flange, but in other respects the blanks from which the top and bottom of the connection and their flanges are made are alike and as the blanks for the 40 two ends and their flanges are alike only the blanks for one-half of a connection is illustrated, it being understood, that the other side is like it with the exception above noted as to the narrower lower flange.

45 The top member of the connection 7 and its flange 8 are formed from a single metal sheet bent on a line $a-b$, which extends between V-shaped marginal indents 9, that define a pair of tongues on each end which are 50 folded on the lines $c-d$, and $e-f$, to form a lock-joint with the connection ends and flanges, the notches being provided to remove the adjacent metal and thereby prevent interference there when the top and 55 flange are bent to final position, on the line $a-b$.

The end 10 has top and bottom extensions 11 and 12 which are bent double on line $g-h$ to interlock with the respective folded ends of top 7, and the end 10 also has 60 an inner extension 13 that is folded at right angles on the line $i-j$ back of flange 14.

The flange 14 has an edge extension which is folded on the line $k-l$ to interlock with top and bottom flanges 8 where opposite 65 them, and to reinforce the inner edge of the flange 14 therebetween. Flanges 14 are wider than flanges 8 to cover wall openings of different lengths.

By the above construction the longitudinal 70 members 7 and the flanges 8 at right angles thereto are integral with each other thereby making a strong and rigid structure. The ends 10 are connected with the members 7 by lock-joints that increase the rigidity of 75 the device, and enable the members 7 and 10 to be readily made of any required dimensions to suit the needed extension beyond the flanges 8 and 14, which varies with the distance of the radiator from the wall of the 80 room in which it is installed. The flanges 8 and 14 are placed against the plastered or otherwise finished inner wall of the room and the connection is retained in a desired position by nails 16, driven through them 85 into suitably placed wooden headers in the wall 17. The ventilating box 18 has a cast-iron base 19 with a flanged opening on which the members 7 and 10 of my connection are 90 assembled with a sliding fit in the manner shown in Fig. 7.

Having thus fully described my invention, what I claim as new and wish to secure by Letters Patent of the United States, is—

1. The method of making a ventilator box 95 with flanges and a top, which comprises the steps of trimming to size a plurality of separate pieces, bending them at right angles on the line between the top and flange, bending up lock joints in the edges of the various 100 pieces and seaming the lock joints to form a top with four angles and a continuous flange.

2. The method of making a ventilator box with flanges and a top, which comprises the steps of trimming to size separate pieces for 105 the end flanges, end top pieces, and pieces for the side tops and flanges, notching the opposed shorter edges of the pieces which form the side tops and flanges, bending them at right angle on the line between the top and 110 flange, bending up lock joints in the edges of the various pieces and seaming the lock

2
joints to form four angles of the top and a continuous flange.

3. The method making a ventilator box with flanges and a top, which comprises the 5 steps of trimming to size separate pieces for the end flanges, end top, side tops and flanges, bending up lock joints in the edges of the

various pieces and seaming the lock joints to form the four angles of the top and a continuous flange.

Signed at Indianapolis, Indiana, this the 29 day of September, 1921.

CLARENCE C. SHIPP.
